UNITED STATES PATENT OFFICE

99,185

DESIGN FOR A COMBINED MATCH CONTAINER AND TRAY

Gordon Chapman, Delamere, England

Application January 16, 1936, Serial No. 60,628
In Great Britain September 16, 1935

Term of patent 7 years

To all whom it may concern:

Be it known that I, Gordon Chapman, a subject of the King of Great Britain, residing at Woodpeckers, Delamere, county of Chester, England, have invented a new, original, and ornamental Design for a Combined Match Container and Tray, of which the following is a specification, reference being had to the accompanying drawing, forming a part thereof.

The figure is a perspective view of the combined match container and tray, showing my new design.

I claim:

The ornamental design for a combined match container and tray, as shown.

GORDON CHAPMAN.
